Gardner C. Kavanagh, Rochester, N. Y., assignor to Aeolian American Corporation, East Rochester, N. Y., a corporation of New York

Application August 8, 1935, Serial No. 58,017

Term of patent 14 years

To all whom it may concern:

Be it known that I, Gardner C. Kavanagh, a citizen of the United States, residing at Rochester, in the county of Monroe and State of New York, have invented a new, original, and ornamental Design for a Piano Case, of which the following is a specification, reference being had to the accompanying drawing, forming part thereof.

Figure 1 is a front elevation of a piano case showing my design, and Figure 2 is an end elevation.

I claim:

The ornamental design for a piano case as shown.

GARDNER C. KAVANAGH.
